UNITED STATES PATENT OFFICE.

SUSIE REBECCA LEWIS, OF GARNET, WEST VIRGINIA.

WINDOW-SHADE SUPPORT.

1,151,886.

Specification of Letters Patent. Patented Aug. 31, 1915.

Application filed November 10, 1914. Serial No. 871,299.

To all whom it may concern:

Be it known that I, SUSIE R. LEWIS, a citizen of the United States, residing at Garnet, in the county of Kanawha and State of West Virginia, have invented a new and useful Window-Shade Support; and I do hereby declare the following to be a full, clear, and exact description of the invention, such as will enable others skilled in the art to which it appertains to make and use the same.

This invention relates to window shade supports, and an object of the invention is to provide a new and useful support of this nature comprising two members, one being fixed stationary to the window frame and provided with improved guides, in which the other member is adjustably mounted, thereby affording a structure of support designed to fit windows of different widths.

After one member of the support or fixture is secured to the window frame it remains permanently in position, the other member being adjustable to accommodate the length of the shade roller.

In practical fields the details of construction may necessitate alterations, falling within the scope of what is claimed.

The invention comprises further features and combination of parts, as hereinafter set forth, shown in the drawings and claimed.

In the drawings, Figure 1 is a view showing the improved shade support or fixture as applied. Fig. 2 is an enlarged detail view of one of the fixtures detached. Fig. 3 is a plan view partly in section. Fig. 4 is a transverse sectional view on line 4-4 of Fig. 2. Fig. 5 is a detail view of the sliding plate.

Referring more particularly to the drawings, 1 designates the window frame, and 2 denotes a plate, which is fastened to the frame, to remain as a permanent fixture thereon, by means of screws 3. This plate is elongated, and the lower portion of which is provided with an upturned flange 4, thereby forming a guide groove 5. The upper portion of the plate 2 is formed with an outwardly, downwardly, and inwardly extending flange 6, which forms a guide groove 7. The upper wall of the flange 6 is constructed with a slot 8. One end of the groove 7 of each plate 2 terminates in an abutment wall or step 9.

The sliding plate 10 of the curtain support or fixture has its lower edge mounted in the guide groove 5, while its upper portion is provided with a forwardly extending flange 11, which guides in the guide groove 7. The flange 11 is provided with a pair of threaded apertures 12, in which the shanks 13 of the set screws 14 are threaded, said shanks passing through the slot 8, thereby it will be noted that by loosening or tightening the set screws the plate 10 may be adjusted, and held in such adjusted position. One end of the plate 10 is provided with a laterally extending lug 15 having a slot 16 for the reception of one of the pintles of the shade roller 17. The other end of the plate 10 is provided with a similar lateral projection 18 having an aperture 19, to receive the cylindrical pindle 20 of the shade roller. By this construction, it will be noted that either one of the fixtures may be arranged so that either end of the shade roller may be connected to any one of the plates 10. In other words, no care need be exercised, as to whether one certain bracket or fixture is fastened to the left or the right side of the window frame, for the shade roller may be easily attached and adjusted in place, regardless as to which fixture is used on the right or left side of the frame.

The flanges of the plate 2 are provided with graduations 21, whereby the lateral projection of the plate 10 may be set opposite any one of the graduations.

The invention having been set forth, what is claimed as new and useful is:

A shade roller fixture comprising a main plate having its lower portion provided with an upturned flange forming a guide groove between the body of the plate and said flange, the upper portion of the plate having a flange extending forwardly, downwardly and inwardly toward the body of the plate forming a second guide groove, a second plate having its lower edge mounted in the lower guide groove and its upper portion provided with a forwardly extending flange engaging the upper guide groove, the upper flange having an elongated slot, means passing through said slot and being threaded into the forwardly extending flange of the second plate for holding the second plate in adjusted positions, the upper groove having at one end an abutment wall to limit the

second plate in one direction, the second plate having lateral projections, one at each end, one of said projections having a bearing to receive a rectangular pintle of a shade roller, the other projection having an aperture to receive the cylindrical pintle of the shade roller.

In testimony whereof I have signed my name to this specification in the presence of two subscribing witnesses.

SUSIE REBECCA LEWIS.
